UNITED STATES PATENT OFFICE.

IRA A. WEAVER, OF SPRINGFIELD, ILLINOIS, ASSIGNOR TO WEAVER MANUFACTURING COMPANY, OF SPRINGFIELD, ILLINOIS, A CORPORATION OF ILLINOIS.

PRESS FIXTURE.

Application filed September 24, 1923. Serial No. 664,482.

To all whom it may concern:

Be it known that I, IRA A. WEAVER, a citizen of the United States, residing at Springfield, in the county of Sangamon and State 5 of Illinois, have invented certain new and useful Improvements in Press Fixtures, of which the following is a specification.

My present invention pertains to means for facilitating the performance of certain 10 types of work such as riveting, punching, etc., and aims to provide simple and effective means for holding the body to be acted upon by the riveting or other tool in correct and proper relation to the latter during the 15 execution of its functions.

The new and improved appliance may be used in association with a press of any approved style or it may be employed with hand implements such as a heavy hammer or 20 the like.

The novel device is of simple conformation, it is relatively inexpensive to produce, and it assures an ease and correct carrying out of the intended operation because the 25 work and tool or tools are always maintained in proper relation one to the other.

To enable those acquainted with this art to fully understand the invention and its 30 several accruing advantages, I have illustrated a desirable and preferred embodiment of the invention in the accompanying drawing forming a part of this specification and throughout the several views of which like reference characters refer to the same parts.

35 In this drawing

Figure 1 is a fragmentary perspective view of a press equipped with the new device;

Figure 2 is a vertical cross-section on line 40 2-2 of Figure 2, the parts being viewed in the direction indicated by the arrows, and

Figure 3 is a fragmentary, perspective view on a reduced scale illustrating the riveting of a gear of the differential mechanism of an automobile.

Referring to the drawing, it will be perceived that in Figure 1 I have shown two, 45 horizontal, supporting bars or plates 11, 11 spaced apart and constituting the supporting bolster or work-support of a press having an upright operating shaft 12 actuated by any approved means, such as by the handwheel 13 having a screw connection with the shaft, whereby turning of the 55 wheel causes the shaft to descend or rise de-

pending upon the direction of rotation of such wheel, the wheel of course having a large mechanical advantage in the operation of such shaft by reason of the screw connection.

The new appliance comprises a portable base-block 14 resting on the top edges of the supporting-member 11 at 15 and having an intermediate part 16 (Figure 2) extending down between the plates and preventing lateral displacement of the block, the latter having two, spaced, horizontal legs or extensions, 17, 17 of appropriate shape in cross-section and supplied at their ends with short, downwardly-projecting lugs or ears 70 18, 18 positioned outside of the plates 11, 11 precluding sidewise movement of such legs, whereby the block, of which these legs really constitute a part, is effectively held in place against dislodgment.

Element 14 has an upwardly-curved arm or bracket 19 integral therewith, such part terminating in a portion 21 having a bearing to receive a vertically-disposed, riveting, 80 punching or other tool 22 capable of sliding movement in such bearing to perform its work.

Directly beneath this tool, the member 14 has a hole extended vertically therethrough designed to removably or detachably receive 85 a die-block 23 arranged to accommodate dies for different sizes of rivets or to receive a perforated or apertured die so that the punch may be used for punching holes as well as setting rivets and performing 90 other operations.

In order that the work, for instance, the differential ring-gear of an automobile, may be properly supported on the die 23, the extensions 17, 17 of the base-block are each 95 supplied with a plurality of threaded holes 24 any one or more of which is designed to adjustably receive one or more threaded supports or studs 25 on which the work is intended to rest.

Owing to the fact that the punch or other tool has a bearing in the same integral member which supports the work and the die proper, correct alignment of the punch and die is assured at all times which is essential 105 to an exact and correct performance of the tools' action.

Inasmuch as the base casting is open at the bottom between the extensions or legs and is open at one end of the latter, the 110

differential housing containing the ring-gear as commonly used in automobiles can be readily and easily slid into place from the side.

5 The work having been placed in position and supported on the die and studs, the punch is caused to descend and head over the rivet or perform whatever other work is required of it, misalignment of the punch 10 and die, as well as misplacement of work, being impossible if the work is properly positioned in the first place.

As the rivet projects a considerable distance through, the punch must work straight 15 down in order to upset it and fill the hole completely.

If one attempts to upset a rivet cold with a hammer, the end is battered up and bruised and the rivet is not properly de- 20 formed to completely fill the hole.

It has been found difficult also in the average garage, where appliances of this kind are particularly adapted for use, to properly heat the rivets and set them with 25 a hammer or tool without injury to the gear.

As this device is made in a single piece casting, the punch-holder is always in line and good work with inexperienced help can 30 be accomplished with it, without incurring the disadvantages in the ordinary garage specified above.

The invention is not limited and restricted to the exact and precise details of structure 35 presented since these may be modified within comparatively wide limits without departure from the heart and essence of the in-

vention and without the sacrifice of any of its substantial benefits and advantages.

I claim:

1. A portable appliance of the character described adapted for use on a press, comprising in combination, a base adapted to rest on the bed of the press having horizontal extensions spaced apart and separated at 40 their ends remote from said base leaving a vertical unobstructed opening between said extensions, an arm upstanding from said base and having a portion overlying the latter, a punch-bearing in said portion, means on said base in alignment with said punch-bearing to receive a complementary die, and adjustable abutments on said extensions to support the work to be acted upon by the punch and die. 50

2. A portable appliance of the character described adapted for use on a press, comprising in combination a base adapted to rest on the bed of the press having horizontal extensions spaced apart and separated at 60 their ends remote from said base leaving a vertical unobstructed opening between said extensions, an arm upstanding from said base and having a portion overlying the latter, a punch-bearing in said portion, said base having a die-receiving recess in register with said punch-bearing, said extensions having a plurality of threaded sockets in 65 their top faces on opposite sides of said opening, and threaded work-supporting studs in 70 said sockets.

In witness whereof I have hereunto set my hand and seal.

IRA A. WEAVER. [L. s.]
